UNITED STATES PATENT OFFICE.

ROBERT GILMORE MCKEE, OF PERU, INDIANA.

WASTE RETAINER FOR JOURNAL BOXES.

1,416,105.

Specification of Letters Patent. Patented May 16, 1922.

Application filed August 17, 1921. Serial No. 492,998.

To all whom it may concern:

Be it known that I, ROBERT G. MCKEE, a citizen of the United States, residing at Peru, in the county of Miami and State of Indiana, 5 have invented certain new and useful Improvements in Waste Retainers for Journal Boxes, of which the following is a specification.

This invention relates to an improvement 10 in devices for retaining or holding in place the fibrous or other material usually employed in journal boxes to supply the journal end of the axle with lubricant from the oil well of the journal box.

15 To that end the invention has particularly in view a so-called "dope" retainer that may be made to fit in all sizes of journal boxes, and when placed in position therein constitutes practical and effective means for 20 holding the lubricating dope in place, thus preventing the same from working the lid of the journal box open and allow oil to bleed from the journal box. By employing a device of this character in journal boxes cotton waste may be efficiently employed in 25 place of woolen waste, thereby effecting a material economy in the upkeep and maintenance of proper journal box conditions.

A further object of the invention is to provide a device that is simple and cheap to manufacture and which may be easily and quickly removed and replaced without inconvenience and with a minimum of manual effort.

35 With the above and other objects in view which will more readily appear as the nature of the invention is better understood, the same consists in the novel construction, combination and arrangement of parts, hereinafter more fully described, illustrated and claimed.

A preferred and practical arrangement of the invention is shown in the accompanying drawings, in which:

45 Figure 1 is a vertical sectional view of a journal box showing the application of my invention.

Figure 2 is a vertical cross-sectional view thereof.

50 Figure 3 is a perspective view of my improved device.

Similar reference characters designate corresponding parts throughout the several figures of the drawings.

55 In carrying the present invention into

effect any suitable and convenient wire or metallic strip may be used to advantage for the purpose of providing the body of the retainer, which is fully shown in Figure 3, and designated generally as R. In the arrangement shown in the drawings the present retainer preferably consists of a single wire w, bent to form the skeleton-like body portion 1 and the rearwardly extending and substantially parallel arms 2-2. The retainer body portion 1 may be formed by zigzag arrangement of the wire, resulting in the looped retaining fingers 3 whose front and rear ends are preferably dipped or bent downwardly as at 4 to more effectively engage the cotton waste and prevent its escape through the lid of the journal box, as will be apparent for example, from Figure 1 of the drawings.

At a substantially intermediate point the 75 rearwardly extending arms 2-2 have suspended therefrom in any suitable manner a depending strap or loop 5, preferably of the same material as the body of the retaining frame and attached thereto in a suitable and convenient manner, as for example, the manner shown in Figure 3 where the ends of the strap are simply looped about the arms 2-2 and located in the keeper depressions 2a to prevent the shifting of the 85 loop on the arms.

When the device is in use the same is applied as shown in Figures 1 and 2 of the drawings. The depending strap or loop 5 is preferably wrapped or enclosed by a portion of the waste or "dope" so that the journal end of the axle is always insured a supply of oil from the lubricant well, while at the same time the bulkiness of the "dope" around the loop or strap serves to hold the 95 body w of the waste in place at the rear end of the journal box. The fingers 3 of the retaining body 1 located between the front end of the axle and the opening of the journal box also serve to hold the body of waste 100 y below the level of the journal box opening and thus prevent its escape. When the device is in use it will be apparent that the tendency of the frame to be ejected or worked out of the box will be resisted by reason of 105 the loop or strap 5 being arranged below the journal end of the axle A, while at the same time the lateral shifting of the frame will be prevented due to the fact that the strap or loop 5 with its surrounding waste or 110

"dope" is anchored in the main body of waste confined within the bottom of the journal box in the well known manner.

Without further description it is thought that the features and advantages of the present device will be readily apparent, and its adaptation and use as a horizontal member for holding the lubricating "dope" in place will be readily appreciated by those familiar with the art. It will of course be understood that changes in the form, proportions and minor details of construction will be resorted to without departing from the spirit of the invention or scope of the appended claims.

I claim:—

A waste retainer for journal boxes includ-

ing in combination with the journal box and the journal end of the axle therein, a horizontally disposed waste retaining frame of 20 skeleton formation adapted to be located between the end of the axle and the opening in the journal box and having rearwardly extending arms, an anchoring strap depending from said arms and adapted to be positioned beneath the journal end of the axle to prevent the said retaining frame from working upwardly.

In testimony whereof I hereunto affix my signature in the presence of two witnesses. 30

ROBERT GILMORE MCKEE.
